CLAIM

The ornamental design for an electric mop as shown and described.

DESCRIPTION

FIG. 1 is a first perspective view of an electric mop showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second perspective view thereof; and,

FIG. 9 is an enlarged top view of FIG. 6 taken at area 9. The broken lines shown in the drawings represent portions of the electric mop that form no part of the claimed design.

1 Claim, 9 Drawing Sheets
